UNITED STATES PATENT OFFICE.

ERNEST E. MARSH, OF YPSILANTI, MICHIGAN.

DESIGN FOR A SEAT-CUSHION.

59,900.

Specification for Design.

Patented Dec. 6, 1921.

Application filed March 25, 1921. Serial No. 455,656. Term of patent 3½ years.

To all whom it may concern:

Be it known that I, ERNEST E. MARSH, a citizen of the United States, residing at Ypsilanti, in the county of Washtenaw and State of Michigan, have invented a new, original, and ornamental Design for a Seat-Cushion, of which the following is a specification, reference being had to the accompanying drawing, forming part thereof.

Figure 1 is a plan view of a seat cushion, showing my new design, and

Fig. 2 is an edge elevation of the same.

I claim:—

The ornamental design for a seat cushion, as shown.

ERNEST E. MARSH.
